Specification for Design.

Patented Mar. 21, 1922.

Application filed August 31, 1921. Serial No. 497,386. Term of patent 7 years.

To all whom it may concern:

Be it known that I, ERIC A. HAWARD, a subject of Great Britain, residing at Woodstock Corner, Bedford Park, town of Chiswick, county of Middlesex, London, England, have invented a new, original, and ornamental Design for Fabric, Paper, or Similar Article, of which the following is a specification, reference being had to the accompanying drawing, forming part thereof.

The figure is a plan view of a portion of a printed fabric showing an embodiment of my new design.

I claim—

The ornamental design for fabric, paper, or similar article, substantially as shown.

ERIC ARNOLD HAWARD.
